UNITED STATES PATENT OFFICE

96,280

DESIGN FOR A PIN OR LIKE ORNAMENTAL EMBLEM

Sidman Ruskin, Chicago, Ill., assignor to F. H. Noble & Co., Chicago, Ill., a corporation of Illinois

Application May 6, 1935, Serial No. 56,702

Term of patent 14 years

To all whom it may concern:

Be it known that I, Sidman Ruskin, a citizen of the United States, residing at Chicago, in the county of Cook, State of Illinois, have invented a new, original, and ornamental Design for a Pin or Like Ornamental Emblem, of which the following is a specification, reference being had to the accompanying drawing, forming a part thereof.

In the drawing Figure 1 is a front elevational view of a pin showing my new design; and Fig. 2 is a side elevational view of the same, the catch of the pin being shown in dotted lines.

I claim:

The ornamental design for a pin or like ornamental emblem, substantially as shown and described.

SIDMAN RUSKIN.
